UNITED STATES PATENT OFFICE.

ERIC G. BJORKLUND, OF BRIDGEPORT, CONNECTICUT, ASSIGNOR TO THE LAKE
TORPEDO BOAT COMPANY, OF BRIDGEPORT, CONNECTICUT, A CORPORATION
OF MAINE.

TORPEDO GUIDE FOR TORPEDO TUBES.

Application filed August 18, 1922. Serial No. 582,749.

To all whom it may concern:

Be it known that I, ERIC G. BJORKLUND, a citizen of the United States, residing at Bridgeport, in the county of Fairfield and 5 State of Connecticut, have invented a certain new and useful Improvement in Torpedo Guides for Torpedo Tubes, of which the following is a full, clear, and exact description.

10 This invention relates to means for discharging torpedoes from the torpedo tubes of vessels of various types and is adapted particularly to the type of stern torpedo tubes shown in the patent of Joseph Barraja - Frauenfelder, No. 1,393,601, granted 15 October 11, 1921.

The object of the invention is to provide means for positively directing the torpedo in its passage from the muzzle of the torpedo tube and until it is clear of the hull of the vessel.

In the construction shown and described in the above mentioned patent, it will be seen that the torpedo tube discharges through 25 an opening directly in the stern of the boat, apertures being provided, intermediate the discharge opening at the stern and the torpedo tube muzzle, through which water is admitted for the purpose of preventing eddies at the stern during firing of the torpedoes, and it will be apparent that when torpedoes are discharged from the torpedo tube in rough water, when the boat is making a sharp turn, or under similar conditions 30 where a cross current is apt to be set up through the openings at the stern of the boat, the torpedo, after it leaves the muzzle of the torpedo tube, may be thrown out of direct line and its steering and driving 35 mechanism injured by contact with parts of the boat. It has therefore been found advisable to provide guides, as hereinafter described, extending from the muzzle of the torpedo tube to the outboard end of the discharge opening.

The invention consists in means for defining the path of discharge of torpedoes, comprising a plurality of guides mounted adjacent to the muzzle of the torpedo tube, 50 and in means for adjusting these guides in operative relation to the tube, as I will proceed now to explain and finally claim.

In the accompanying drawings illustrating the invention, in the several figures of

which like parts are similarly designated, 55 Figure 1 is a partly diagrammatic longitudinal, vertical, sectional elevation of the stern of a submarine torpedo boat showing the application of the invention thereto. Fig. 2 is a vertical cross section taken substantially in the plane of line 2—2, Fig. 1. Fig. 3 is a horizontal section taken substantially in the plane of line 3—3, Fig. 1. Fig. 4 is a fragmentary vertical section similar to Fig. 1, but showing the muzzle door of the 60 torpedo tube in closed position, the other parts being shown in the positions assumed by them with relation to the door. Fig. 5 is a vertical section substantially similar to Fig. 2, but showing the parts in the position 65 shown in Fig. 4. Fig. 6 is a fragmentary vertical section showing the operation of the bottom guide operating cam lug. Fig. 7 is a fragmentary vertical section showing the operation of the releasing lug for releasing 70 the bottom guide and forcing it to operative position.

As in the patent above mentioned so here, 75 the stern of the boat is provided with a post 1 having a cylindrical opening 2 formed 80 therein, and in this opening is mounted a tube 3 supported by ribs 4 and plates 5. 6 designates a torpedo tube arranged in axial alignment with the cylindrical opening 2 of the stern post 1, this tube being provided 85 with a muzzle door 7 carried by lever 8 pivoted at 9 and adapted to be swung about its pivot 9 by means of worm and sector gearing mounted in casing 10 and driven by 90 means operated from within the torpedo control compartment of the boat.

Extending approximately from the end 11 of the tube 3 to the muzzle of the torpedo tube 6 are openings 11', as indicated in Fig. 4, in the sides of the boat through which 95 water may enter, the water so entering having free passage astern through the tube 3. These openings 11' are here shown as slots formed in the hull plating of the boat, but it is obvious that, as in the patent above mentioned, they may be in the form of a single large opening in the side of the boat. These openings may take any other desired or feasible shape or size, and I have therefore shown the slots in only one figure of the drawings to avoid confusion.

As previously pointed out, although these openings in the sides of the boat prevent ed-

dies at the stern of the boat and the consequent probability of such eddies impeding the passage of the torpedo when it is discharged from the torpedo tube, they nevertheless permit cross currents to affect the passage of the torpedo upon its discharge, and, if these cross currents are sufficiently strong make possible side-sway, and dipping and tipping of the torpedo before it is clear of the stern of the boat. In order to prevent this effect of cross currents upon the torpedo, I provide a plurality of guides extending from the muzzle of the torpedo tube 6 to the discharge end of the tube 3. These guides comprise a fixed guide 12 at the bottom of tube 3, and a fixed guide 13 at the top thereof, the guide 13 extending forward and terminating in close proximity to the torpedo tube, muzzle, but allowing sufficient clearance for opening and closing of the muzzle door 7. Guides 14 fixedly arranged diametrically opposite each other at the sides of tube 3 are also provided, and to these guides are hinged at 15 movable guides 16 pivotally connected at 17 with levers 18 pivoted at 19 in fixed bearings 19' and provided with extensions 20 adapted to cooperate with the opposite ends of a pin or bar 21 carried by the lever 8 for a purpose later described. Pivots mounted at 22 to a bracket 23 attached to one of the plates 5 is a movable bottom guide 24 provided with a lever extension 25 terminating in a stop shoulder 25', and a cam face 26 adapted for cooperative engagement with a pair of cams or lugs 27 carried by the muzzle door 7. The guide 24 is also provided with a lip 28 adapted to limit the downward swinging movement of the guide to proper position relative to the torpedo tube and in alignment with the guide 12 by contact with a stop 29 at the muzzle of the torpedo tube 6.

In addition to the cams or lugs 27 the muzzle door is provided with a starting lug 30 and a releasing lug 31 the functions of which will hereinafter appear. As will be seen by reference particularly to Fig. 5, the releasing lug 31 is arranged between the cam lugs 27.

The side guides 16 are provided with stops 32 adapted to abut against diametrically opposite points on the flange 33 of the torpedo tube muzzle for the purpose of aligning the guides 16 with the bore of the torpedo tube and the guides 14.

The operation of the invention is substantially as follows:—Assuming that the muzzle door 7 is, as under ordinary conditions, closed as shown in Figs. 4 and 5, and it is desired to fire a torpedo from the torpedo tube. The muzzle door is opened by proper manipulation of the devices (not shown) for operating the worm and sector gearing contained in the casing 10. This operation of the worm and sector gearing will swing the lever 8 about its pivot 9 and will, at the same time, carry with the lever the muzzle door 7. As the muzzle door 7 swings outwardly from the torpedo tube muzzle, and downwardly, the cam lugs 27 will slide upon the cam surface 26 of the guide 24 until they have passed out of contact with this cam surface, whereupon the guide 24 will be free to swing down upon the edge 34 of the muzzle door, and later on upon the lug 30 finally being brought down to the position shown in Fig. 1 with its lip 28 resting upon stop 29. If, for any reason, the guide 24 should become stuck or jammed in its upward position (Figs. 4, 6 and 7), the cam lugs 27 will straddle the extension 25 of guide 24 as the muzzle door descends, and the releasing lug 31 will contact with the lever extension 25 as shown in Fig. 7 and force guide 24 out of its upward position and thereby permit it to drop to the position shown in Fig. 1. The cooperation of the muzzle door 7 with the stop shoulder 25' locks the guide 24 in aligned position.

At the same time that the guide 24 is being released or forced downward so as to assume the position shown in Fig. 1, the pin or bar 21 is operating upon the extensions 20 of the levers 18 to spread said levers apart and thereby move the guides 16 on their hinges 15 so that stops 32 will contact with the flange 33 of the torpedo tube muzzle, in which position, as above pointed out, the guides 16 are in alignment with the bore of the torpedo tube and the guides 14, the pin or bar 21 acting to hold the guides 16 in such proper alignment so long as the muzzle door is in its full open position, as shown in Fig. 1.

With all the guides in their properly aligned position, it will be seen that in effect a continuation of the torpedo tube is provided from the muzzle of the torpedo tube to the outboard end of the cylinder 3, and any side-sway dipping or tilting of the torpedo during its passage from the torpedo tube outboard will be prevented.

After the torpedo has been discharged, the muzzle door may be closed by reverse rotation of the worm and sector gearing and the guides will be returned to their inoperative positions in the following manner:—As the muzzle door swings upward and inward, towards the torpedo tube muzzle, the starting lug 30 will first come in contact with the lower side of the guide 24 and start the guide in its upward swinging movement about its pivot 22. As the upward and inward movement of the muzzle door continues the cam lugs 27 will contact with the cam face 26 of the guide 24 and will raise the guide to the position shown in Figs. 4, 6 and 7, and when the door is completely closed, as shown in Fig. 4, the ends of the cam lugs 27 will hold the guide in its upper position as shown. While this actuation of the guide 24 is taking place, the pin or bar

21 is riding upward out of contact with the cam extensions 20, and, when the muzzle door comes in contact with the guides 16, these guides will be forced to swing outwardly upon their hinges 15 so as to permit the muzzle door to close.

Thus it will be seen that I provide means for guiding the torpedo during and after its discharge from the torpedo tube, whereby its 10 steering and driving mechanism are protected against injury, these means being automatic in their operation and requiring no operating means other than the means connected with and adapted to open and close 15 the muzzle door, all of the mechanism for operating the movable guides being actuated by parts associated with and carried by the muzzle door.

The invention is not limited to the use of 20 worm and sector gearing for opening and closing the muzzle door.

Although I have herein shown and described a particular embodiment of my invention, it is to be understood that I do not consider it as limited thereto, as various changes may be made in details of construction and arrangement of parts without departing from the spirit of the invention or the scope of the following claims; and, although the invention is shown and described as applied to the stern torpedo tube of a submarine boat, it is obvious that it is well adapted for use with torpedo tubes in other positions and in various types of vessels.

35 What I claim is:—

1. In a vessel, having a torpedo tube terminating within its hull and a discharge opening in said hull, the combination with said tube of guides extending therefrom to the opening in the hull and terminating within said hull.

2. In a vessel having a torpedo tube terminating within its hull and a discharge opening in said hull, the combination with said tube of a plurality of guides extending therefrom to said hull opening, portions of said guides being movable.

3. In a vessel, a torpedo tube having its muzzle arranged within the hull of the vessel, a torpedo discharge opening extending through said hull and in axial alignment with said tube, water inlet openings in said hull intermediate said tube muzzle and discharge opening, two pairs of stationary guides arranged in said discharge opening, the upper guide of one pair extending toward and terminating in proximity to said tube muzzle and spanning said water inlet openings and fixed with relation to said tube, and movable guides adapted when in adjusted position to form extensions of the remainder of said stationary guides to span said water openings.

4. In a vessel, having a torpedo tube the muzzle of which is arranged within the hull

of the vessel, a torpedo discharge opening in said hull and communicating with the sea, water inlet openings in said hull intermediate said tube muzzle and discharge opening, said discharge opening forming a water outlet for said water inlet openings, stationary guides at the top, bottom and sides of said discharge opening, said top guide terminating in proximity to said tube muzzle and said bottom and side guides terminating adjacent said water inlet openings, and movable guides forming when in adjusted position continuations of said last mentioned stationary guides and movable into and out of adjusted position for the purpose specified, said movable guides spanning said water inlet openings.

5. In a vessel, having a torpedo tube the muzzle of which is arranged within the hull of the vessel and a discharge opening in said hull, the combination with said tube of guides extending therefrom to said hull opening, portions of said guides being movable, means for closing the muzzle of said tube, and cooperating means on the movable portions of said guides and said muzzle-closing means for actuating the movable portions of said guides.

6. In a vessel, having a torpedo tube, the combination with said tube of a plurality of movable guides adapted to be positioned in alignment with said tube but normally out of such alignment, means for closing the muzzle of said tube, and cooperating means on said guides and muzzle closing means for moving said guides into and out of alignment with said tube.

7. In a vessel, having a torpedo tube, the combination with said tube of a plurality of movable guides adapted to be positioned in alignment with said tube but normally out of such alignment, means for closing the muzzle of said tube, and cooperating means on said guides and muzzle closing means for moving said guides into and out of alignment with said tube and for holding them in such positions.

8. In a vessel, having a torpedo tube, the combination with said tube of a plurality of movable guides, a muzzle door for said torpedo tube, and cooperating means on said door and guides for moving said guides into and out of operative position relative to said tube.

9. In a vessel, having a torpedo tube, the combination with said tube of a plurality of guides, portions of which are movable, a muzzle door for said tube, and cooperating means on said muzzle door and the movable portions of said guides whereby said movable portions are moved into and out of operative relation with respect to said torpedo tube.

10. In a vessel, having a torpedo tube the muzzle of which is arranged within the hull

- of the vessel and a torpedo discharge opening in said hull, the combination with said tube of a plurality of guides extending between the muzzle thereof and said discharge opening, a portion of each of said guides being movable and the other portion thereof being fixed in axial alignment with said torpedo tube, a muzzle door for said tube, means for operating said muzzle door, and cooperating means on said door and on the movable portions of said guides whereby the movable portions of the guides may be moved into and out of operative relation with respect to said tube.
15. 11. In a vessel, having a torpedo tube, the combination with said tube of a torpedo guide pivotally mounted with respect to said tube, a muzzle door for said tube, a cam lug on said door, and a cam surface on said guide adapted to cooperate with the cam lug on said door whereby said guide may be moved into and out of operative alignment with respect to said tube.
20. 12. In a vessel, having a torpedo tube, a pair of guides pivoted with respect to said tube, a muzzle door for said tube, a lever by which said muzzle door is carried and by means of which it may be opened and closed, levers cooperating with said guides and provided with extensions, and means operative with said muzzle door for actuating said extensions to move said guides into and out of operative alignment with respect to said tube.
25. 13. In a vessel, having a torpedo tube, the combination with said tube of a plurality of guides provided with movable extensions, the movable extension of one of said guides pivoted for swinging action upon a horizontal axis, and the movable extensions of the others of said guides pivoted for swinging action upon vertical axes, a muzzle door for said torpedo tube, an operating lever for said door, means on said door for actuating the guide extension pivoted upon a horizontal axis to move the same into and out of operative alignment with respect to said tube, levers pivoted to a stationary portion of said boat and connected with the extensions of the guides movable upon vertical axes, and means carried by said door operating means and cooperating with said levers for moving said vertically pivoted portions into and out of operative alignment with respect to said tube.
30. 14. In a vessel, having a torpedo tube the muzzle of which is arranged within the hull of the vessel and a discharge opening in said hull in axial alignment with said torpedo tube, a plurality of stationary guides arranged in said discharge opening one of same extending into proximity to the muzzle of said torpedo tube and the others terminating at a distance therefrom, a plurality of movable guides adapted when in adjusted position to form continuations of said last mentioned stationary guides, a muzzle door for said torpedo tube, and means operative coincidently with the opening and closing of said muzzle door for moving said movable guides into and out of operative alignment with respect to said tube.
35. 15. In a vessel, having a torpedo tube the muzzle of which is arranged within the hull of the vessel and a discharge opening in said hull in axial alignment with said torpedo tube, a plurality of stationary guides arranged in said discharge opening, one of which extends into proximity to the muzzle of said torpedo tube and the others terminate at a distance therefrom, a plurality of movable guides adapted when in adjusted position to form continuations of said last mentioned stationary guides, a muzzle door for said torpedo tube, and means operative coincidently with the opening and closing of said muzzle door for moving said movable guides into and out of operative alignment with respect to said tube the 75
40. 16. The combination with a torpedo tube, of a torpedo guide pivoted with respect to said tube, a lever extension on said guide, a muzzle door for said torpedo tube, a cam lug and a releasing lug on said door, and a cam surface on said guide, said cam lug adapted to turn said guide upwardly about its pivot by cooperation with said cam surface, and said releasing lug adapted by cooperation with said lever extension to release said guide from its upward position.
45. 17. The combination with a torpedo tube, of a pair of guides arranged laterally with respect thereto, hinge members for said guides about which the guides may swing into and out of operative alignment with respect to the bore of said tube, stops on the swinging ends of said guides adapted to abut against the sides of said tube to limit their swinging action toward said tube to a position in which they are in alignment with the bore thereof, levers pivoted in bearings fixed with relation to said tube, said levers being connected with said guides and having cam extensions, a muzzle door for said tube, a lever by which said muzzle door is carried and by means of which the door may be swung to open and closed positions, and means carried by said door carrying lever and cooperating with the extensions of said first mentioned levers whereby when said door is opened, said guides will be moved into operative alignment with respect to the bore of said tube and when said door is closed said guides will be moved out of such alignment to permit the passage of the door therebetween.
50. 18. The combination with a torpedo tube, 120
55. 19. The combination with a torpedo tube, 125
60. 20. The combination with a torpedo tube, 130

of a torpedo guide pivoted with respect thereto, a cam surface on the under side of said guide, a muzzle door for said torpedo tube, means for opening and closing said door, a cam lug on said door adapted to cooperate with the cam surface on said guide, a starting lug on said door adapted to cooperate with the under side of said guide whereby when said door is moved to close the muzzle of said tube, said starting lug

5

10

will impart an initial raising movement to said guide and said cam lug will thereafter during the closing movement of said door

continue the raising movement of said guide, and a stop fixed with respect to said tube for 15 limiting the lowering movement of said guide to a position in which the guide is in operative alignment with the bore of said tube.

In testimony whereof I have hereunto set 20 my hand this 16th day of August A. D. 1922.

ERIC G. BJORKLUND.
